Inventor:

David Gates.

By his Atty.

I Franklin Reigart.

UNITED STATES PATENT OFFICE.

DAVID GATES, OF CAPTINA POST OFFICE, OHIO.

CHURN.

Specification forming part of Letters Patent No. 64,758, dated May 14, 1867.

To all whom it may concern:

Be it known that I, DAVID GATES, of Cap-
tina Post Office, Belmont county, State of
Ohio, have invented new and useful Improve-
ments in Churns; and I do hereby declare the
following to be an exact description thereof,
reference being had to the accompanying draw-
ings, and to the letters of reference marked
thereon, making a part of this specification,
in which—

Figure 1 represents a side elevation of the
churn; Fig. 2, a vertical section of the churn;
Fig. 3, a top view of the radial dashers; Fig.
4, a front elevation of the churn and devices.

A A represent the ordinary crank, toothed
wheels, and fly-wheel attached to an upright
frame, B, to give rapidity of motion to the
upright pitman and shaft C.

The nature of my invention consists in the
arrangement and construction of the two ra-
dial dashers fitting closely to the inside of the
churn with the posts P P P and tube M; also,
the mode of bracing the churn firmly on the
outside to the frame.

D represents a cross-brace, against which
the churn E rests. The churn E is made of
staves, straight on the inside and inclined on
the outside. The circular dashers G have ra-

dial apertures or arms H, the arms H on the
lower dasher being opposite to the apertures
on the upper dasher, the peripheries of the two
dasher G working closely up and down against
the inner straight side of the churn E, so as to
force the cream through the apertures and
against the arms H as they move up and down,
thoroughly breaking the cream, and the dasher
G are supported by three upright posts, P P
P. An adjustable cross-piece, J, that fits into
the mortise or notch K of another adjustable
brace, L, holds the churn firmly to its place
during the operation of churning. The shaft
C works in a tube, M, and the lower dasher G
operates upon the tube M, so as to operate the
dasher perfectly perpendicular.

What I claim as my invention, and desire to
secure by Letters Patent, is—

The construction of the radial dashers G,
with center tube M, between the posts P P P
and cross-braces J and L, when constructed,
arranged, and operated as herein described,
and for the purposes set forth.

DAVID GATES.
